United States Patent Office

Des. 178,668
Patented Sept. 4, 1956

178,668

HEADBOARD FOR A CHILD'S BUNK BED.

Clarence P. Jensen, Madison, Wis.

Application July 9, 1954, Serial No. 31,363

Term of patent 14 years

(Cl. D5—4)

I claim:

The ornamental design for a headboard for a child's bunk bed, as shown.
